UNITED STATES PATENT OFFICE

JOHN KAY, OF INDIANAPOLIS, INDIANA.

IMPROVEMENT IN ROLLER-ABSTRACTERS FOR LEVER-WATCHES.

Specification forming part of Letters Patent No. **149,760**, dated April 14, 1874; application filed January 28, 1874.

To all whom it may concern:

Be it known that I, JOHN KAY, of the city of Indianapolis, county of Marion, State of Indiana, have invented a Roller-Abstracter for Lever-Watches, of which the following is a specification:

My invention relates to a sliding spindle worked by a screw with a swivel-point within an appropriately-shaped guide and nut, in combination with two adjustable spring-legs with suitable feet, in such a manner that when the spring-legs and feet are set to clasp the under side of the roller attached to the staff of a lever-watch, the sliding spindle may be made to press on the top of the staff, forcing the staff through the hole in the roller, and abstracting the roller easily, and without injuring any of the parts attached to the staff.

Every watch-maker knows the extreme difficulty there is in taking the roller off the staff without injuring either balance-wheel, roller, or staff, or loosening the staff in the balance-wheel. Especially is this true in a compensating balance; and in many Swiss lever-watches the roller is placed so close down to the hub of the balance that it makes it even more difficult to take the roller off without injury to the watch. With my roller-abstracter, no matter how awkwardly the roller is set, or how tight it is fastened to the staff, it comes off easily and safely.

In the accompanying drawings, Figure 1 is a perspective elevation of my roller-abstracter, shown in connection with the staff, roller, &c. Fig. 2 is a sectional elevation of the same.

A is the body of the abstracter, made of any suitable material and shape, and having a hole drilled longitudinally through it. The upper part of the hole is smaller in diameter, and forms the nut in which the screw B works. To the lower end of B is attached, by a swivel-joint, b, the sliding spindle C, fitting closely the larger parallel hole drilled in A. The lower part or nipple of C is made smaller in diameter and tapering, the extreme end having a shal-

low conical hole sunk in its center to receive the end of the watch-staff. This nipple can either be made solid with the spindle C or detachable. D D are spring-legs fastened to A at the top, and having feet d turned in, as shown, and shaped to fit under the roller. The legs D can be adjusted to suit different diameters of staff and rollers by the screw E and nut e, an elongated slot, c', being cut in C to allow the spindle to work up and down without interfering with the screw E. f is the watch-staff, to which is attached the roller F and balance-wheel G.

The operation of my abstracter can be best described by referring to the drawings. The abstracter is shown there as adjusted ready to force the staff through the roller. One or two turns on the screw B is sufficient, and the roller is detached, leaving the balance-wheel on the staff intact. By having a hollow nipple to receive the staff, and placing the feet to clamp the lower end of the staff, my abstracter can also be used to force the roller on. By lowering the nipple e, it would carry before it the roller F to any point desired, the spindle rising within the nipple.

I claim as my invention—

1. The adjustable spring-legs D, with inverted feet d, in combination with the sliding adjustable spindle C, moving between, and independently of, the said spring-legs, substantially as specified.

2. The sliding spindle C, with slot c' and solid or detachable nipple e, working within the guide cut in A, the screw B, and swivel-point b, working within the guide and nut in A, in combination with the adjustable spring-legs D, with feet d, the screw E, and nut e, arranged substantially as described, and for the purpose specified.

JOHN KAY.
